DESIGN FOR A PLATE OR THE LIKE

George Wesp, Forest Hills, N. Y., assignor to Continental Ceramics Corporation, New York,
N. Y., a corporation of New York

Application August 14, 1937, Serial No. 71,088

Term of patent 7 years

To all whom it may concern:

Be it known that I, George Wesp, a citizen of the United States of America, residing at Forest Hills, in the county of Queens and State of New York, have invented a new, original, and ornamental Design for a Plate or the like, of which the following is a specification, reference being had to the accompanying drawing, forming part thereof, in which Fig. 1 is a top plan view of a plate, showing my new design; Fig. 2 is a sectional view along line 2—2 of Fig. 1, and Fig. 3 is a sectional view along line 3—3 of Fig. 1.

I claim:

The ornamental design for a plate or the like, as shown.

GEORGE WESP.
